UNITED STATES PATENT OFFICE.

EMMA HAGEMEISTER, OF NEW YORK, N. Y.

HAIR WAVER.

Application filed April 24, 1925. Serial No. 25,681.

To all whom it may concern:

Be it known that I, EMMA HAGEMEISTER, a citizen of the United States of America, and a resident of the city of New York, 5 borough of Manhattan, in the county and State of New York, have invented a new and Improved Hair Waver, of which the following is a description.

My invention relates to a hair waver employing combs capable of relative movement to give a wave formation to the hair.

The present invention is in some respects designed as an improvement on the hair waver forming the subject of an application 15 filed in the name of W. N. Lurcott, under date of December 17, 1924, Serial Number 756,505.

The prime object of the present invention is to provide a hair waver having instrumentalities that will produce a Marcel wave 20 and in a manner to give reasonable permanency to the wave.

The nature of my invention and its distinguishing features and advantages will 25 clearly appear as the description proceeds.

Reference is to be had to the accompanying drawings forming a part of this specification, it being understood that the drawings are merely illustrative of one example 30 of the invention.

Figure 1 is a plan view of a hair waver embodying my invention, a plurality of the swinging elements to be hereinafter mentioned being shown raised and a pair of said 35 swingable elements being shown in the lowered position at the top of said figure;

Figure 2 is a fragmentary horizontal section on the line 2—2, Figure 4;

Figure 3 is a transverse vertical section 40 as indicated by the line 3—3, Figure 1 but showing all the swingable elements in a partially lowered position ready to engage the hair;

Figure 4 is a longitudinal vertical section 45 through my improved hair waver;

Figure 5 is a detail in transverse vertical section showing a pair of the swingable elements lowered to a position to engage the hair, and another pair of the swingable elements in a higher position;

Figure 6 is a fragmentary end view of the hair waver;

Figure 7 is a fragmentary view in longitudinal vertical section given to show another form of the fixed combs.

In carrying out my invention in practice any suitable frame and supporting means are provided, there being shown a fragment of a standard 10 having a fitting 11 secured thereto by a bolt 12 and wing nut 13. The fitting 11 is received between depending bracket members 18 on the frame 17 and bolts 16 having nuts 14 and washers 15 are passed through the bracket members 18 and through the fitting 11. The frame and supporting means form no part of the present invention.

I provide a series of fixed combs and a series of shiftable combs. The movable combs 20 are arranged in pairs the combs of a pair being disposed at the opposite sides of each fixed comb. A plurality of the fixed combs 19 are in rigid relation to electric heating elements 21. Other fixed combs 119 alternate with those combs 19 associated with the electric heating elements 21, said fixed combs 119 being rigid with the frame 17. The combs 20 of a pair are integral with each other through the medium of a U-shaped base 22 which extends about the under side of each heating element 21 so as to have guided movement on said heating element. The base 22 has an extension 122 at each end which extends through the ends 117 of the frame 17.

When a strand of hair (A) is laid across the device through the several combs, the movement of the combs 20 relatively to the fixed combs 19 and 119 will produce waves in the strand of hair as indicated at the top of Figure 1. The device therefore constructed as described will effectively produce waves in the hair.

In order that a Marcel wave be produced, I provide means to engage the waves of the hair at the sides of the comb. In the illustrated example, I provide blades or plates 23 arranged in pairs, plates of a pair being integral with each other at an end thereof, said end being secured as by a pivot 24 to a fixed part at an end of the hair waver. The opposite end of each pair of plates 23 has a handle 25. Said plates 23 are adapted to be lowered from the dotted line position, Figure 4, to the position shown at the left of Figure 5 in engagement with and exerting pressure upon hair waves. The pivot 24 it will be observed from Figure 4 is located above the plane of the bases or backs of the combs 19, 20. The result is

that the plates 23, when fully lowered to operative position between the combs, will exert equal pressure along strands of hair run through the combs at different points as shown in Figure 4. At the opposite ends of the frame 17 are fixed carrying handles 26. In the Lurcott application referred to above, means is provided to operate the movable combs. The present invention embodies a slight modification of the aforesaid means in said filed application. Thus, the integral pairs of combs 20 are each operated through the medium of a vertical spindle 30 having a head 31 and depending from the frame 17. The spindle extends through the bottom of the frame and has a lever 32 fixed thereon which is pivoted at one end as at 33 to a link 34, the opposite end of which is pivoted as at 35 to the base 22 of a pair of combs 20. The described operating means is provided for each pair of combs 20. As in the aforesigned application the lever 32 at the opposite end from the pivot 33 has a stud 37 adapted to engage in any one of an arcuate series of depressions 36 in frame 17. The positioning of the lever with the stud 37 in a given depression 36 will cause a given length of wave in the strand of hair A. The engagement of the stud 37 with a depression 36 serves to lock the lever 32, spindle 30, and link 34, as well as the combs 20 actuated by the link, in fixed position, said locking means and its function corresponding with the means and the mode of functioning thereof disclosed in the aforesigned filed application.

In the use of the device a strand of hair is disposed transversely between the teeth 40 of the fixed and movable combs with the teeth alined. Then, the movable combs are shifted by turning the spindles 30. In practice, one pair of fixed combs 20 is actuated first, then the adjacent pair of fixed combs, 45 and so on in succession. After the hair has been waved by the shifting of the movable combs relatively to the fixed combs, the plates or blades 23 are brought down and they move in planes in close relation to the 50 movable combs in a manner that when said blades are brought down, pressure is exerted by the same against the sides of the respective waves.

In the form shown in Figure 7 an additional feature is provided to hold the hair against rising on the combs. Said feature consists of slots 319 formed in one edge of

the fixed combs 219 at the base thereof and extending longitudinally so that as the movable combs are shifted, the strand of 60 hair will move into the slots 40.

I would state in conclusion that while the illustrated example constitutes a practical embodiment of my invention, I do not limit myself strictly to the exact details herein 65 illustrated, since, manifestly, the same can be considerably varied without departure from the spirit of the device as defined in the appended claims.

Having thus described my invention, I 70 claim:

1. A hair waver including a series of combs, and a second series of combs movable longitudinally relatively to the first combs to produce a wave in a strand of hair, said 75 first-mentioned combs being formed with longitudinal slots in the teeth thereof at the base of the teeth for holding the strands of hair against displacement along the 80 combs.

2. A hair waver including a series of combs, and a second series of combs movable longitudinally relatively to the first combs to produce a wave in a strand of hair, said 85 first-mentioned combs being formed with longitudinal slots in the teeth thereof at the base of the teeth for holding the strands of hair against displacement along the combs; together with means movable between the teeth and into engagement with 90 a strand of hair to exert pressure on the waved strand or to a position out of engagement with the hair permitting release of the same.

3. A hair waver including two series of combs, one series shiftable longitudinally relatively to the other for waving a strand of hair, and swingable elements mounted to move in a plane between fixed and movable combs, or to a position away from the combs for engaging the waved strand of hair, the teeth of the combs being formed with means to engage the strand of hair and prevent its moving lengthwise of the teeth of the combs. 95

4. A hair waver including heating elements, a series of fixed combs in rigid relation to the heating elements in the general longitudinal plane thereof, additional fixed combs alternating with the first mentioned fixed combs, and movable combs alternating with the fixed combs and shiftable longitudinally thereto. 100 105 110

EMMA HAGEMEISTER.
